UNITED STATES PATENT OFFICE.

SIMON COOPER, OF BROOKLYN, NEW YORK, ASSIGNOR TO ALLISON BISHOPRIC, OF CINCINNATI, OHIO.

MACHINE FOR THE MANUFACTURE OF WALL BOARD.

Application filed April 3, 1920. Serial No. 371,004.

To all whom it may concern:

Be it known that I, SIMON COOPER, a citizen of the United States, residing at Brooklyn, in the county of Kings and State of New York, have invented certain new and useful Improvements in Machines for the Manufacture of Wall Board, of which the following is a specification.

My present invention relates to wall board and to automatic apparatus for the manufacture of the same.

The objects of the invention are to provide a practical, durable and relatively light but strong wall board, so constructed that the plaster will firmly adhere thereto and to provide practical and efficient mechanism for rapidly and automatically manufacturing the board.

The invention involves numerous novel features of construction, combinations, relations and arrangements of parts, as set forth in the following specification, reference being had to the accompanying drawings forming a part hereof and in which the invention is disclosed in practical commercial forms, it being understood, however, that the invention is not limited to the particular forms disclosed, but is of broader scope, as will be clear from the appended claims.

In said drawings, Figure 1 is a side view of the machine with parts indicated as broken away.

Figure 2 is an enlarged vertical sectional view of the lath and web assembling mechanism.

Figure 3 is a further enlarged and sectional view illustrating details of the lath feeding and positioning devices.

Figure 4 is a broken view of the assembling head structure as slightly modified in certain respects.

Figure 5 is a composite sectional and face view of the carrier wheel for the spacing fingers.

Figure 6 is a face view and Figure 7 is a sectional view of the adjustable member for supporting the finger actuating cams.

Figure 8 is a broken plan view of the assembling head structure illustrating slight modifications in the method of driving the rollers which press the laths onto the drum.

Figure 9 is a broken detail view of a section of the completed wall board.

My improved wall board as shown in the

view last referred to comprises a web 10 of 55 heavy paper, cardboard or other suitable backing material having secured to the face thereof in spaced relation the strips 11 forming the laths to which the plaster or other construction material is applied. These 60 laths are usually in the form of wooden strips and according to a preferred embodiment they are formed with beveled side edges 12 and applied with the narrower face thereof in contact with the backing so as 65 to provide the undercut dovetail plaster keying grooves 13.

These laths are secured to the web in properly spaced relation preferably by means of a suitable adhesive and by mechanism like that to be now described.

In the general view, Figure 1, the web 10 is shown as passing over and about feed rolls 14, 15 and then over guide rolls 16, 17 to an adhesive-applying roll 18, the web being drawn over the top of the adhesive roll by the cooperating pinch rolls 19, 20 and passing from there between the cooperating press rolls 21, 22 which operate to apply the 75 laths to the web.

The guide roll 16 is shown as driven from the main shaft 23 by a belt or chain connection 24 and the feed roll 15 is indicated as driven from the shaft 25 of feed roll 16 by a belt or chain connection 26, the 85 other feed roll 14 being connected with feed roll 15 by suitable gearing 27. The lower pinch roll 19 is indicated as driven from the guide roll shaft 25 by the chain of gearing 28, 29, 30, 31, the last gear 31 being fast on the pinch roll shaft 32 and the cooperating gear 30 being fast on the shaft 33 of the adhesive-applying roll. This arrangement causes the pinch roll to rotate in a direction to draw the web forward 90 while the adhesive roll rotates in the reverse direction and, therefore, wipes the adhesive on the under face of the web and in a direction reverse to the travel thereof. As the web travels around the upper pinch 95 roll 20 it is reversed so as to bring the adhesive coated surface uppermost.

Asphalt or other suitable adhesive may be employed for securing the slats on the web and said adhesive may be applied either hot 100 or cold, depending upon its nature and also upon the characteristics of the laths and the webbing. In the illustration I have indi-

cated the adhesive as supported in a heated tank or reservoir 34 within which the adhesive-applying roll rotates. The use of asphaltic adhesive is preferred on account of its lasting, preservative and weather-proof qualities.

The amount of adhesive is controlled in the machine illustrated by relatively adjusting the pinch rolls between which the adhesive coated web passes. For this purpose I have shown the upper pinch roll 20 as journaled in swinging arms 35 pivoted on the main frame at 36 and adjusted at the opposite ends of the roll by the screws 37 operated by the hand wheels 38. It will be evident that by the adjustment of these screws the space between the rolls may be increased or diminished to regulate the thickness of the film of adhesive and to control the gripping effect exerted by these rolls on the web. The independent adjustment at the opposite ends of the rolls makes it possible to correct any irregularities that may occur at this point.

25 The laths are supplied to the assembling mechanism by a conveyor indicated at 39, shown in Figure 1 as having a substantially horizontal portion 40 for receiving the laths and a downwardly inclined run 41 for carrying the same down beneath the fingers which transfer the laths over to the assembling roll 22. This conveyor is furthermore shown as provided with spaced studs or lugs 42 for holding the laths in definitely spaced relation and as driven by a belt or sprocket connection 43 from the main drive shaft 23.

The spaced laths are transferred from the conveyor chains 39 onto the upper press roll 22 by transfer fingers 44. These fingers, as shown particularly in Figures 2, 3 and 5 are slidingly guided in substantially radially formed slots 45 provided in the concentric annular flanges 46, 47 on the carrier wheels 48. The spacing fingers are slidably confined in these slots provided in the face of the carrier wheels by the overlying cam supports indicated at 49 in Figure 8 and which supports carry the cam tracks 50, 51 and 52 operating on the cam rolls 53 on the fingers for projecting and retracting the same in the guide slots. The cam track 51 is shown as yieldingly mounted on the face of the cam support 49 as by means of a spring 54 so as to enable the projecting fingers to yield inwardly in the event of encountering an obstruction.

In the course of the travel from the conveyor chains over onto the assembling drum, 60 the slats are supported on the bridge pieces 55 which extend from the end of the conveyor on a line gradually merging into the periphery of the drum.

The drum is provided with devices for 65 holding the slats in the same spaced relation

at which they have been fed to the drum, such devices being herein illustrated as the projecting points 56 on the peripheral portion of the drum, said points being spaced in any desired relation and disposed so as to engage the slats either at the ends or at intermediate portions thereof. A variable spacing of these points is provided for in the illustration (Fig. 3) by providing these points on supporting segments 57 which are 75 removably and interchangeably applied to the periphery of the drum.

To insure positive engagement of the laths on the holding points, I have illustrated at 58 presser wheels for forcing the 80 slats down over the upstanding pins substantially at the point where the slats meet the periphery of the drum. These impaling rolls are shown in Figures 1, 3 and 8 as journaled in the ends of the supporting arms 59 pivoted on the shaft 60 and as driven by sprocket chains 61 from the shaft 60 which is operated from the assembling drum by a gear 62 in mesh with the drum gear 63.

In Figure 4 the impaling rolls 58 are shown as supported by pivotal arms 59 but in this instance the drive is accomplished from the shaft 60 through the medium of idlers 64 journaled on the supporting arms 59 and meshing at one side with gears 65 fast on shaft 60 and at the opposite side with gears which are fast to the impaling rolls.

In both constructions the impaling rolls are shown as yieldingly forced toward the 100 drum by the springs 66 operating on the roll supporting arms and which if desired, may be adjustable.

The laths after being thus applied in the desired spaced relation to the assembling drum are preferably positively held thereto in the course of the rotation of the drum by yieldable means comprising in the illustration the flexible chains 67 secured at their lower ends to the brackets 68 and extending from a point (Fig. 2) adjacent the pitch line of the two press rolls upwardly about the side and over the top of the upper roll where they pass over guide rolls 69 and 70, the weight 71 being shown as applied to the ends thereof for yieldingly holding the same under the desired tension. The guide rolls 69 for the upper ends of the holding chains are shown as mounted on the free ends of the swinging arms 59 (Fig. 8) so that the springs 66 acting on said supporting arms also exert a certain tension on the guide chains.

The operation of the parts thus far described is as follows: The web of backing material is first advanced by the feed rolls 14 and 15, either or both of which may, if desired, be heated as by means of steam for the purposes of drying the web or heating it so as to better take up the adhesive. As the web

passes over the adhesive-applying roll a film of the asphaltic or other adhesive is applied to the under face thereof, the amount or thickness of which coating is governed by the pinch rolls, the upper one of which serves to reverse the web so as to bring the adhesive coating uppermost. The bevel edged slats or laths are placed on the conveyor 39 with the narrower faces outward (Figs. 2 and 3) and are transferred by the transfer fingers in this relation over onto the upper portion of the assembling drum, to which they are temporarily affixed, in the spaced relation determined by the spacing fingers, by means of the impaling wheels. The laths are positively held in this relation during the rotation of the drum by the surrounding guard chains 67 and are released from such confinement at or before the point where the slats meet the adhesive face of the web passing over the lower press roll 21. The assembling roll thus serves as a means for reversing the slats so as to bring the narrower faces thereof into engagement with the adhesive on the web and the two rolls are so adjusted as to exert sufficient pressure to cause the laths to firmly adhere to the web. For this latter purpose I have shown the upper roll as journaled in sliding boxes 72 acted on by the springs 73.

The assembled product issuing from between the two cooperating press elements is suitably guided out of the machine and may be cut in desired lengths.

At 74 in Figure 2 I have illustrated stripper fingers pivoted on a shaft 75 at the exit side of the drum and having pointed or beveled ends yieldingly held by the springs 76 in the grooves 77 provided in the periphery of the drum. These fingers operate to positively strip the slats from the drum and operate as guides to hold the slats down onto the web to which they have just been applied, thus in effect, holding them in place while the adhesive is setting.

The edges or selvage portions of the product may be trimmed as it leaves the machine by means of suitable saws or trimmers, indicated at 78 in Figure 1.

Provision is made in this invention for varying the spacing of the slats on the backing material and this is accomplished in the machine illustrated by simply varying the effective length of the transfer fingers by raising or lowering the carrier wheels with respect to the cam mechanism which projects and retracts the fingers. In Figure 1 the carrier wheel shaft 79 is shown as supported in spring-pressed boxes 80 working in guide slots in the supporting arms 81 which are pivoted at 82 and are operated by hand wheels 83 through the medium of worm gearing 84 and screws 85. It will be evident that by operating the hand wheels 83 the supporting arms 81 may be swung one way

or the other for the purpose of raising and lowering the carrier wheels and that this raising or lowering of such wheels will increase or decrease the extent of projection of the transfer fingers. The spacing at the 70 ends of these fingers will be greater the further they are projected and hence, within the limits of the machine the slats may be applied to the assembling drum in any spaced relation desired. The transfer fingers thus 75 operate as a variable spacing means for transferring the slats from the definitely spaced conveyor chains over onto the drum which is arranged to take the slats in the relation to which they have been adjusted by 80 the spacing fingers and to apply the same in such relation to the backing material. Another advantage of this spacing adjustability of the transfer fingers is that it enables the machine to handle slats of different 85 width and thickness.

Details of a suitable form of drive gearing and adjustment mechanism for the carrier wheel are shown in Figure 4. In this view the carrier wheel shaft 79 is shown as provided with a gear 86 in mesh with a gear 87 on the shaft 82 of the lath conveyor and these gears are held constantly in mesh irrespective of the adjustment of the carrier wheels by means of the links 88 pivoted at their opposite ends to the shafts 82 and 79. In this particular construction the boxings 80 of the shaft 79 are adjusted in guide slots 89 formed in the links 88 which are pivoted at their lower ends to the shaft 91 of the assembling drum and the adjustment is effected by the screw 92 operated from the hand wheel 93 through the worm gearing 94.

Figure 4 also illustrates how the drum gear 63 and gear 62 may be maintained in proper relation irrespective of the vertical yielding movements of the drum, the means provided for this purpose comprising spacing links 95 connected at their upper ends with the drive shafting 60 and pivoted at 100 their lower ends at 96 to the bearings or boxings for the drum shaft. This upward or outward shifting movement of the shafting 60 is shown as opposed by the springs 97. From the construction described, it will 105 be apparent that the gearing of the entire assembling head may be maintained in proper meshing engagement irrespective of the adjustments made.

It will be apparent that the machine may 110 be operated to produce different styles and sizes of wall board and it will further be apparent that the wall board disclosed while relatively inexpensive is thoroughly practical and desirable. In addition to adjusting the thickness of the film of adhesive, the mounting of the upper pinch roll disclosed 115 enables said roll to be thrown back to facilitate the introduction of the web into the machine. Another point which is quite impor- 120 125 130

tant in the operation of the machine is the tapering of the lower end of the chain supporting bracket 68 as shown in Figure 2, so as to enable the same to form a guide or 5 guard extending quite close to the web adjacent to where the slats come into engagement with the web. This serves to maintain the slats under control substantially up to the time that they are actually impressed upon 10 the backing material.

What I claim is:

1. In a wall board machine, cooperating press rolls, means for feeding between said rolls a web supplied on one face thereof 15 with adhesive, means for supplying laths in spaced relation to the adhesive side of said web and including pins on one of the rolls for temporarily holding the laths in spaced relation and means for spacing and 20 impaling the laths in such spaced relation on said pins.
2. In a wall board machine, cooperating press members one at least of which is a rotating press roll provided with devices for 25 temporarily holding laths in spaced relation, means for supplying a web between the press members and means for stripping the laths from the holding devices of the roll.
3. In a wall board machine, cooperating 30 press members one at least of which is a rotating press roll provided with devices for temporarily holding laths in spaced relation, means for supplying a web between the press members, means for stripping 35 the laths from the holding devices of the roll and including yieldingly supported fingers engaging in grooves in the press roll beneath the level of the laths carried thereby.
4. In a wall board machine, cooperating 40 press members, one at least of which is a rotating roll, spaced pins on said roll for temporarily holding laths, means for impaling laths in desired predetermined spaced 45 apart relation on said pins and means for supplying a web between the press members.
5. In a machine of the character described, a lath conveying roll having 50 removable segments on the peripheral portion thereof provided with outstanding points spaced to engage spaced laths applied to the periphery of the roll.
6. In a machine of the character described, a lath conveying roll having 55 removable segments on the peripheral portion thereof provided with outstanding points spaced to engage spaced laths applied to the periphery of the roll and means 60 for forcibly pressing the laths onto said spaced points.
7. In a machine of the character described, a lath conveying roll having removable segments on the peripheral portion thereof provided with outstanding 65

points spaced to engage spaced laths applied to the periphery of the roll, means for forcibly pressing the laths onto said spaced points and means for stripping the laths from said holding points. 70

8. In a machine of the character described, a lath conveying roll provided with spaced projecting points on the periphery thereof, means located at one point about the periphery of the roll for forcing laths in spaced relation onto said points and means disposed at a different point about the roll for stripping the spaced laths from said holding points. 75

9. In a machine of the character described, a lath conveying roll provided with spaced projecting points on the periphery thereof, means located at one point about the periphery of the roll for forcing laths in spaced relation onto said points, means 80 disposed at a different point about the roll for stripping the spaced laths from said holding points and including yieldingly supported stripper fingers, the roll having grooves disposed below the level of the applied laths to receive said fingers. 85

10. In a machine of the character described, a press bed, a press roll cooperating therewith and provided with means for holding laths in spaced relation thereon, means for feeding a web between the bed and roll, a flexible guide extending about the roll to a point adjacent the entry of the web between the cooperating press elements described and a stripper disposed at the opposite exit side of said elements for positively separating the laths 90 from the holding devices on the roll. 100

11. In a wall board machine, a lath conveying roll, a lath conveyor, spacing fingers for transferring the laths in spaced relation from the conveyor to said roll and means for varying the spacing of said fingers to thereby vary the spaced relation of the laths carried by the roll. 110

12. In a machine of the character described, a conveyor provided with means for transporting laths in definite spaced relation, a conveyor for carrying the laths in variously spaced relations, and transfer means interposed between said conveyors for changing the spacing of the laths during their period of travel from the definitely spacing conveyor to the variable spacing conveyor. 115

13. In a machine of the character described, a conveyor provided with means for transporting laths in definite spaced relation, a conveyor for carrying the laths in variously spaced relations and adjustable means for transferring the laths in different desired spaced relations from the definitely spacing conveyor to the variable spacing conveyor. 125

14. In a machine of the character de- 130

- scribed, a conveyor provided with means for transporting laths in definite spaced relation, a conveyor for carrying the laths in variously spaced relations, and transfer means interposed between said conveyors for changing the spacing of the laths during their period of travel from the definitely spacing conveyor to the variable spacing conveyor, said variable spacing conveyor comprising a rotating drum provided with spaced projecting lath impaling points. 5
15. In a machine of the character described, a conveyor provided with means for transporting laths in definite spaced relation, a conveyor for carrying the laths in variously spaced relations, means interposed between said conveyors for changing the spacing of the laths during their period of travel from the definitely spacing conveyor to the variable spacing conveyor and including variably spaceable traveling fingers. 10
16. In a machine of the character described, a conveyor provided with means for transporting laths in definite spaced relation, a conveyor for carrying the laths in variously spaced relations, means for transferring the laths in the desired spaced relation from the definitely spacing conveyor to the variable spacing conveyor, including variably spaceable traveling fingers and adjustable cam mechanism for controlling the spacing of such fingers. 15
17. In a machine of the character described, a conveyor provided with means for transporting laths in definite spaced relation, a conveyor for carrying the laths in variously spaced relations, means for transferring the laths in the desired spaced relation from the definitely spacing conveyor to the variable spacing conveyor and including variably spaceable traveling fingers and yieldable supporting means for said fingers. 20
18. In a machine of the character described, a conveyor provided with means for transporting laths in definite spaced relation, a conveyor for carrying the laths in variously spaced relations, means for transferring the laths in the desired spaced relation from the definitely spacing conveyor to the variable spacing conveyor, including variably spaceable traveling fingers and a yieldable supporting cam operating on said fingers. 25
19. In a machine of the character described, a conveyor provided with means for transporting laths in definite spaced relation, a conveyor for carrying the laths in variously spaced relations, means for transferring the laths in the desired spaced relation from the definitely spacing conveyor to the variable spacing conveyor and including a bridge for supporting the laths and spaced fingers traveling over said bridge. 30
20. In a machine of the character de- scribed, lath spacing and transferring means comprising a wheel provided with substantially radial guide-ways, projecting fingers mounted in said guide-ways and cam mechanism operating on said fingers to project and retract the same in the course of the rotation of said wheel. 35
21. In a machine of the character described, lath spacing and transferring means comprising a wheel provided with substantially radial guide-ways, projecting fingers mounted in said guide-ways and cam mechanism operating on said fingers to project and retract the same in the course of the rotation of said wheel, said cam mechanism including a section yieldably supported to enable the projecting fingers to yield inwardly. 40
22. In a machine of the character described, lath spacing and transferring means comprising a wheel provided with substantially radial guide-ways, projecting fingers mounted in said guide-ways, cam mechanism operating on said fingers to project and retract the same in the course of the rotation of said wheel and means for relatively adjusting the wheel and cam mechanism to vary the extent of projection of the fingers. 45
23. In a machine of the character described, lath spacing and transferring mechanism comprising a rotating support provided with guide passages, fingers guided in said passages, a support adjustable with respect to said rotary support and cam mechanism on said adjustable support for operating on the fingers aforesaid. 50
24. In a machine of the character described, lath spacing and transferring mechanism comprising a rotating support provided with guide passages, fingers guided in said passages, a support adjustable with respect to said rotary support, cam mechanism on said adjustable support for operating on the fingers aforesaid and including cam tracks, the fingers having rollers riding on said cam tracks. 55
25. In a machine of the character described, a wheel provided with substantially radial guide slots in one face thereof, fingers guided in said slots, a member engaged over the face of said wheel and over the fingers guided in said slots, a cam carried by said member and operating on the fingers and means for shifting the cam supporting member relative to the finger guiding wheel. 60
26. In a machine of the character described, a slat conveying roll, spacing and feeding fingers for advancing slats in spaced relation to said roll, said feeding fingers and roll being relatively adjustable and means for driving both the same irrespective of their relative adjustment. 65
27. In a machine of the character described, a slat conveying roll, a wheel provided with projecting fingers for feeding 70
- 75
- 80
- 85
- 90
- 95
- 100
- 105
- 110
- 115
- 120
- 125
- 130

- slats in spaced relation to said roll, means for adjusting the finger wheel with respect to the conveying roll and means for driving the roll and wheel irrespective of their relative adjustment.
28. In a machine of the character described, a conveyor roll provided with projecting spaced points on the peripheral portion thereof, means for feeding slats in spaced relation onto the periphery of said roll and means for yieldingly pressing the slats thus applied onto the projecting points of the roll.
29. In a machine of the character described, a conveyor roll provided with projecting spaced points on the peripheral portion thereof, means for feeding slats in spaced relation onto the periphery of said roll, means for yieldingly pressing the slats thus applied onto the projecting points of the roll and means for yieldingly holding said slats on the points during the travel of the roll.
30. In a machine of the character described, means for transferring laths in spaced relation consisting of a carrier wheel, fingers projecting substantially radially from said wheel and means for projecting said fingers to different lengths.
31. In a machine of the character described, means for transferring laths in spaced relation consisting of a carrier wheel, fingers projecting substantially radially from said wheel, means for projecting said fingers to different lengths comprising a relatively stationary cam for engaging the fingers and means for bodily adjusting the carrier wheel with respect to said cam.
32. In a machine of the character described, combining rolls for pressing laths in spaced relation onto a web, a conveyor for feeding laths in spaced relation and adjustable means for changing the spacing of the laths between the conveyor and the combining rolls.
33. In a machine of the character described, combining rolls for pressing laths in spaced relation onto a web, a conveyor for feeding laths in spaced relation and adjustable means for changing the spacing of the laths between the conveyor and the combining rolls and comprising a rotating carrier provided with variably projectable radial fingers.
34. In a machine of the character described, a roll provided with projecting pins, means for forcing laths onto said pins, means for feeding a web to the laths on said roll and means for releasing the laths from said pins after contact of the laths with the web.
35. In a machine of the character described, a wheel provided with substantially radial guide slots in one face thereof, fingers guided in said slots, a member engaged over the face of said wheel and over the fingers guided in said slots, a cam carried by said member and operating on the fingers and means for relatively shifting the cam supporting member and finger guiding wheel.
36. In a wall board machine, means for introducing laths into the machine in a definite spaced relation, a lath conveyor, and an adjustable transfer means for variably spacing the introduced laths onto the lath conveyor.
37. In a wall board machine, means for transporting laths, a lath conveyor and adjustable means for transferring the laths to from the transporting means to the lath conveyor.
38. In a wall board machine, means for transporting laths, a lath conveyor, and an adjustable rotary means for transferring the laths from the transporting means to the lath conveyor.
39. In a machine of the character described, a lath conveying roll having removable segments on the peripheral portion thereof provided with lath holding means to positively engage spaced laths applied to the periphery of the roll.
40. In a wall board machine, cooperating press members one at least of which is a rotating press roll provided with devices for temporarily holding laths in spaced relation, means for supplying a web between the press members and yieldingly supported fingers for stripping the laths from the holding devices of the roll.

In testimony whereof I affix my signature.

SIMON COOPER.
